UNITED STATES PATENT OFFICE.

THOMAS C. KELLER, OF DIXON, ILLINOIS.

DESIGN FOR AN EAVES-TROUGH SCREEN.

SPECIFICATION forming part of Design No. 30,107, dated January 31, 1899.

Application filed January 9, 1899. Serial No. 701,679. Term of patent 14 years.

To all whom it may concern:

Be it known that I, THOMAS C. KELLER, a citizen of the United States, residing at Dixon, in the county of Lee, State of Illinois, have invented a certain new and original Design for an Eaves-Trough Screen, of which the following is a specification, reference being had therein to the accompanying drawings, in which—

10 Figure 1 is a perspective of an eaves-trough screen. Fig. 2 is a central vertical section thereof, and Fig. 3 is a top plan view.

As shown in the drawings, the leading or material feature of the design is the curved 15 base-line A and the curved lines B, extending therefrom upon a greater arc than the line A. The lines A and B terminate at a

horizontally-curved line C, below which extend a vertically-curved line D and a tapering curved line E. Above the curved line A 20 extends a curved outline A', merging at one end into a horizontal line A'.

Having described my invention, what I claim as new, and desire to secure by Letters Patent, is—

The design for an eaves-trough screen, as herein shown and described.

In testimony whereof I affix my signature in presence of two witnesses.

THOMAS C. KELLER.
